SELF-PRIMING PUMP CONSTRUCTION

Richard G. Barzen, Kansas City, Mo.

Application May 24, 1930. Serial No. 455,238

1 Claim. (Cl. 103—113)

This invention has relation to pumping apparatus, and my primary object is to devise an improved pump construction of the centrifugal action type in which is incorporated a simple and efficient self-priming means for starting the vacuum action of the pump.

Accordingly, my invention comprises an improved self-contained construction in which the primer feature is substantially built in as a unitary part of the pump and possesses various advantages in the way of utility and efficiency over pump priming apparatus commonly constructed.

It is also sought to provide a unitary construction in which the primer operation may be carried out either automatically or by means of an auxiliary hand-operated pumping device forming part of the equipment.

Having the foregoing general objects in view, the invention will now be described by reference to the accompanying drawing illustrating one practical form of embodiment thereof, after which the novel features and combinations considered patentable will be set forth and claimed.

In the drawing—

25 Figure 1 is an elevation illustrating a pumping device constructed in accordance with the invention, one face of the pump housing being removed;

30 Figure 2 is a vertical sectional elevation, looking in the opposite direction, and representing a section on a line 2—2 of Figure 3; and

35 Figures 3 and 4 are horizontal and vertical sections taken on lines 3—3 and 4—4 respectively, of Figure 2.

40 Referring to the drawing in detail, the apparatus is illustrated as comprising a main casting 5, in one face of which is formed a volute pumping chamber 6 over which is secured by bolts 7 a face or cover plate 8 provided with a stuffing box 9 for the shaft 10 of the rotor or impeller member 12, as shown in Figure 4. The opposite face of the casting member 5 is formed as a two-compartment housing divided by a partition 14 into a suction or receiving compartment 15 and an outlet or discharge compartment 16, at the top of which is connected the discharge conduit 17. A web or partition 18 separates compartments 15 and 16 from the pump chamber 6, which communicates with the compartment 15 by way of the opening 20 concentric with the pump chamber as represented in Figure 1, and located at the bottom of the larger portion of the chamber 15, as represented in Figures 2 and 4. The pump supply or receiving line 22 is connected with the top of the chamber 15, as illustrated in Figures 3 and 4.

The pump discharges through an outlet 24 (see Figures 1 and 2) into the lower reduced portion of the housing compartment 16, the upper larger portion of which compartment is provided with a curved or angular baffle element 14' formed as 60 a projection from the lower upright portion of the partition 14, the upper portion of said element being bent or curved in the direction of the upper portion of said partition which is provided with a port 25 affording communication between the 65 upper portions of the compartments 15 and 16.

A port 26 is also provided in the web or partition 18 as a communicating passage between the pump chamber 6 and the upper portion of the outlet compartment 16. 70

At the top of the housing portion of the main casting member 5 is also mounted a conventional type of hand pump 28 for use as required, or when desired to supplement the automatic priming action of the pump. 75

In the operation of the pump, a supply of water is maintained in the chambers thereof as represented in Figure 2. On starting the pump action, a circulation of this water (with any air contained therein) is produced, from the pump chamber 6, 80 out through the passage 24 into the compartment 16 and then back to the pump chamber by way of the ports 25 and 26. Inasmuch as the pump action will pull air in by way of the supply or suction line 22 and through the compartment 15, 85 such air will be entrained in the liquid, and discharged into the compartment 16 and released by the successive pockets of water discharged therethrough. The released air will tend to escape by the discharge pipe conduit 17, as facilitated by the curve of the baffle element 14', which also serves as a shield between this discharge current and the port 25. The water settling down from this combined air and water current, finds its way through the port 26, back into the pump 90 chamber 6, and is once again circulated, and is recirculated until the air is completely exhausted from the suction line; after this takes place, the flow through the opening 26 will be reversed, said port thereafter acting simply as a discharge port, 95 so that no loss in pump-discharging capacity is suffered by any further recirculation of the water priming supply through this port. 100

It is apparent therefore that a compact and self-contained construction is provided in which the self-priming structure is formed substantially as an integral part of the pump itself; and that not only is an efficient priming action produced so long as the necessity for the priming function exists, but when the air is exhausted from the 105

suction line, the port 26 reverses its function from that of a return passage to that of a discharge passage, thereby preserving the full capacity of the pump for its normal pumping function. The 5 structure of the baffle 14' in the chamber 16 is designed to facilitate the separating action between the water and the air, and incidentally helps to shield the port 25 from any disturbing action of the current discharging into the outlet 17, and 10 is also beneficial as a shield to this zone at times when an auxiliary air pump is in use.

The function of the opening 25 is primarily to break the vacuum on stopping the pumping operation, and prevent all the water from being 15 completely siphoned out of the pump chambers; thus a sufficient amount of water for the primary operation is trapped and maintained in the pump chambers at all times. It is this water of course which seals the discharge line 20 during the primary operation, by preventing the leakage of air back from the discharge line 17 into the vacuum or suction line 22. The size of the port 25 need not be large enough to constitute any appreciable leak or loss in the pumping 25 capacity after the pump is primed.

The construction is also of a design well adapted for the mounting of any suitable type of positive displacement air pump, such as a hand pump 28, in efficient operative relationship to the primary pump structure, as an accessory 30 for either reinforcing the self-priming function

or as a substitute therefor under some circumstances.

It will thus be seen that a simple and compact construction of practical and efficient design is thereby provided for carrying out the aforesaid objects of the invention, and while the form of construction illustrated and described is deemed that best suited to the purpose in view, it is desired to expressly reserve the right to make such changes or modifications as may fairly fall within the scope of the appended claim.

Having described the invention, what I claim and desire to secure by Letters Patent is:

A self-priming pump construction comprising a pump casing providing an impeller chamber and a housing provided with an irregular baffle partition dividing the housing into a receiving compartment having an enlarged lower portion in communication with the impeller chamber intake and a discharge compartment having a reduced lower portion in communication with the pump discharge, means providing a combined recirculating and direct pump discharge passageway between the upper portion of said discharge compartment and the periphery of the impeller chamber, and a baffle member projecting from said partition in position to shield said passageway from the main discharge current from the pump.

RICHARD G. BARZEN.
